DESIGN FOR A SADDLE

Roland W. Faulhaber, Elyria, Ohio, assignor to
The Troxel Mfg. Company, Elyria, Ohio, a cor-
poration of Ohio

Application December 11, 1935, Serial No. 60,015

Term of patent 7 years

To all whom it may concern:

Be it known, that I, Roland W. Faulhaber, a citizen of the United States, residing at Elyria, in the county of Lorain and State of Ohio, have invented a new, original, and ornamental Design for a Saddle, of which the following is a specification, reference being had to the accompanying drawing, forming a part thereof, in which:

Fig. 1 is an elevational view taken from the right-hand side of a saddle showing my new design;

Fig. 2 is a rear elevational view of the saddle of Fig. 1 drawn to a slightly larger scale;

Fig. 3 is an elevational view of a part of the saddle of Fig. 1 taken from the left-hand side of the saddle and drawn to a larger scale;

Fig. 4 is a sectional view taken approximately from the plane 4—4 of Fig. 3 showing the cross-sectional profile of the part shown in Fig. 3.

I claim:

The ornamental design for a saddle substantially as shown.

In testimony whereof, I hereunto affix my signature this 2nd day of December, 1935.

ROLAND W. FAULHABER.
